SPINNING, DOUBLING, AND TWISTING
MACHINERY

Sebastian Ziani de Ferranti, deceased, late of Hollinwood, England, by Gertrude Ruth Ziani de Ferranti, executrix, Upper Basildon, Pangbourne, England, assignor to Ferranti Inc., New York, N. Y.

Original application February 8, 1934, Serial No. 710,366, now Patent No. 2,010,179. Divided and this application December 31, 1934, Serial No. 760,002. In Great Britain February 13, 1933

3 Claims. (Cl. 117—32)

This invention relates to thread severing devices for spinning, doubling and twisting machinery, especially to machines of the high speed flyer type and to thread severing devices which 5 become operative to prevent the passage from the cop to the spinning device of snarls, knots or enlargements of the thread.

In such machines it is very desirable that 10 irregularities in the thread should not be allowed to reach the spinning devices as serious effects on the machine or product might ensue.

The present invention is concerned with a device which is interposed between the feeding cop and the feed rolls of the spinning device which 15 will automatically sever the thread soon after the passage of the irregularity from the cop.

The object of the invention is to provide a device of this character which is cheap and simple and practically infallible.

20 A further object consists in providing improvements in construction and arrangement of the several parts of such devices.

The invention consists in a device of the character above indicated in which the passage of 25 an irregularity is hindered by an adjustable arresting device which in its turn operates a scissors device through which the thread normally passes on its way to the feed rolls of the spinning device.

30 The invention also consists in the features of construction and operation of the several parts of the device which is hereinafter fully described with reference to the accompanying drawings.

Referring to the accompanying drawings, 35 Figure 1 is a diagrammatic elevation of a spinning machine embodying the device according to the invention.

Figure 2 is a part sectional elevation of the 40 yarn delivering and tensioning part of Figure 1.

Figure 3 is a side elevation of a balance lever in running position.

Figure 4 is a plan view of Figure 3.

Figure 5 is a reversed side elevation of balance 45 lever in position caused by an obstruction in the yarn and showing cutter operating mechanism in dotted lines.

Figure 6 is a section on the line 6—6 of Figure 3.

Figure 7 is a section on the line 7—7 of Figure 5 to a larger scale.

50 Figure 8 is a side elevation of a balance lever in position taken up when yarn breaks.

Figure 9 is an underside view of the cutters shown to a larger scale than in Figure 5.

Referring to Figures 1 and 2, the feed of yarn 55 takes place from the cops 101, through the ten-

sioning device 103, over the pulley 113 at the end of the balanced arm 102, thence over the pulleys 147 and 152, through an eye 79, under a lower roll 80, between the lower and an upper roll 81, over the upper roll and down through the top of the flyer 1. The balance arm 102 is raised to such a height above the feed rolls 80, 81 or the length of thread between the severing device of the balance arm 102 and the feed rolls is made so great that should a thread be severed 10 a single length will not fall from the top into the rotating parts, and so cause an entanglement before the flyer has been brought to rest.

For doubling, the cops are arranged in pairs, doubling being effected from the cops directly. 15 The thread from each cop is passed as before mentioned through a tension device 103.

From this tensioning device the yarn passes to the balance arm 102 referred to above. This balance arm consists of an aluminium or like 20 framework 110, having two points of suspension 111 and 112. It is provided at one end with a pivoted roll 113 fitted with the clearer assembly 114 described below, and a counterbalance 115 at the other, so that of itself it normally tends 25 to sit with the roll 113 elevated. When the frame is running the balance arm rests on both pivots, being kept in this position owing to the friction on the yarn introduced by the tensioning device. This friction is insufficient to cause the balance 30 arm to pivot only on the pivot 111 nearer the roll should the pull on the yarn become too great, owing to some defect in the yarn on the clearer, on the roll, referred to below, or owing to a hold-up on the cop, the balance arm pivots 35 on the forward pivot only.

The clearer assembly 114 consists of a grooved pulley 115 having a U shaped groove 116 with which a pin 117 co-operates. The pin is made of such a size, and the grooves of such a depth, that it will not pass faulty yarn, which latter would become impaled on the spike and cause the lever 110 to tip on to the forward pivot 111.

The pin referred to above is mounted in a 45 spring controlled frame 118. The balance arm is provided with a thread severing device 119 disposed in the vicinity of the grooved pulley and consisting of a scissors device, the movable part 120 of which is operated by a wire 121a connected with a light pivoted frame 122, one end of which 50 projects through a slot 121 in the framework 110, in the vicinity of the forward pivot 111. The shape of this slot and the position of the projecting part is such that when the arm 110 pivots about the rear pivot 112, the projection 55

from the scissors operating frame 122 is quite clear of the side of the slot 121 in which the scissors projection rides, but when the arm 110 is caused to pivot about the forward pivot 111, the side of the slot 121 catches the projection, causing it to ride backwards in its own slot 121 and sever the yarn.

On the yarn being severed, the arm 110 becomes free, and assumes the position corresponding to position of equilibrium, which may be vertical or substantially so as controlled by the general framework of the machine.

This application is a division of my application No. 710,366, filed February 8, 1934, now Patent No. 2,010,179 dated August 6, 1935.

Having now described the invention, what is claimed as new and desired to secure by Letters Patent is:—

1. An automatic device for severing an individual yarn in a high speed spinning machine which includes means responsive to the passage of an irregularity in the yarn into the said automatic device and means operated by the said responsive means to sever the thread, characterized in that the said responsive means include a rockable arm having two parallel lateral pivoting axes, a fixed abutment for coacting with said axes, a grooved yarn guiding pulley, a clearer device and a scissors device so arranged on one end of said arm that the yarn passes normally

through the clearer device, over the grooved pulley and through the open scissors device, the other end of said arm carrying a counter weight sufficient to cause the arm to rest on both pivots simultaneously during normal operation, and means operated by the downward displacement of the pulley end of said arm consequent upon the passage of an irregularity into the clearer device to close the scissors device and thus sever the thread.

2. An automatic device for severing yarn as claimed in claim 1, the said latter means comprising a lever projecting from the side of said rockable arm and adapted to coact with the said fixed abutment, a movable blade of said scissors device and a link connecting said movable blade with said lever.

3. An automatic device for severing yarn as claimed in claim 1 the said clearer device comprising a pointed member fixed to the same end of the rockable arm as the guide pulley and arranged to point in the opposite direction to the normal run of the yarn to form with the groove in the said grooved pulley an aperture through which normal yarn may pass without hindrance a scissors device arranged on the run of the yarn.

GERTRUDE RUTH ZIANI DE FERRANTI,
Executrix of the Estate of Sebastian Ziani de Ferranti, Deceased.
